UNITED STATES PATENT OFFICE.

EDWARD D. DOUGHERTY, OF PHILADELPHIA, PENNSYLVANIA.

GRIP FOR CABLE RAILWAYS.

SPECIFICATION forming part of Letters Patent No. 351,901, dated November 2, 1886.

Application filed May 17, 1886. Serial No. 202,437. (No model.)

To all whom it may concern:

Be it known that I, EDWARD D. DOUGHERTY, of Philadelphia, in the county of Philadelphia and State of Pennsylvania, have invented 5 certain new and useful Improvements in Grips for Cable Railways; and I do hereby declare the following to be a full, clear, and exact description of the invention, such as will enable others skilled in the art to which it appertains 10 to make and use the same.

My invention relates to an improvement in grips for cable railways.

The object is to provide a grip which will automatically release itself from the cable when 15 allowed so to do by the operating-lever, and in which gravity shall be employed to accomplish said release.

A further object is to provide a set of yielding rollers adapted to engage the cable and 20 gradually recede until the cable is gripped by a pair of metallic-faced jaws.

A further object is to provide a set of rollers adapted to swing in a vertical plane at right angles to the line of the cable, and to lift and 25 support the cable between the gripping jaws.

With these ends in view my invention consists in certain features of construction and combinations of parts, as will be hereinafter described, and pointed out in the claims.

30 In the accompanying drawings, Figure 1 is a view of the grip in end elevation. Fig. 2 is a view of the same in side elevation. Fig. 3 is a horizontal section through the line $x-x$ of Fig. 1, and Fig. 4 is a section through line $y-y$ of Fig. 1.

A represents the depending support or hanger, to which the grip mechanism is attached.

To one side of the hanger A is secured a flat plate, B, bent outwardly, downwardly, and inwardly at the lower edge, forming in cross-section three sides of a rectangular loop, as shown at $b-b'$. In the end of the loop portion of the plate B are journaled or loosely mounted a pair of upright rollers, C, one at each end, preferably on bolts c , which serve as axles. The bearings of the bolts are in movable boxes D, which are secured in transversely-elongated slots in the parts $b-b'$ of the plate B, and are held in a normally-advanced position toward 45 the gripping-face of the plate B by elastic cushions d , preferably of rubber. Between the rollers C is located a bearing block or plate of

soft metal, E, conveniently held in position by screws through the portion b' of the plate B. The faces of the rollers C project slightly beyond the face of the block or plate E, and the plate B, with its attachments, as described, and the strengthening brace or braces e form what may be properly termed the "stationary jaw" of the grip. 55

To the opposite side of the hanger A is secured a plate, F, provided at or near its lower edge with a pair of perforated lugs, f , to which are hinged the upwardly-extending arms g of the swinging jaw G. The lower portion of the 65 jaw G is shaped quite similarly to the part $b-b'$ b' of the jaw B, and has in its ends a pair of upright rollers, H, secured thereto in the same manner as and opposite to the rollers C. The jaw G is also provided with a soft-metal gripping-plate, I, located opposite the plate E in the jaw B. At the lower edge of the jaw G—one at each corner—are secured horizontal slightly-tapered rollers K, which occupy positions transversely to the line of the cable, and are 70 adapted to support it between the gripping faces of the jaws, and to release and pick it up as the jaw is swung outwardly and inwardly on its hinges. The rollers K are conveniently secured by means of bolts k , which extend through perforated ears or projections formed on the jaw, on which the rollers freely rotate. A laterally and downwardly extending bifurcated arm, L, is secured to the upper portion of the plate F, and in the ends of its branches 75 is secured the bolt M, on which the eccentric or cam wheel N is mounted. The wheel N is adapted, as it rotates on its support, to allow the jaw G to swing outwardly or to force the same inwardly, according as its bulging side 80 is swung away from or toward the back of the jaw. The pitman and lever for operating the wheel N is not shown, but is conveniently connected with the wheel at the point n , and may be of any well-known or approved construction. The jaw G is caused to have a tendency 85 to swing away from the jaw B by a counter-weight, O, secured to the end of a transverse arm, o, attached to the portion of the said jaw which is hinged to the plate F, or otherwise 90 connected with the jaw, so that its depression will tend to swing the jaw outwardly. The counter-weight arm o may work in a slot 95 formed in the plate or jaw B, or it may be lo-

cated at either end of the plate, the object being to give it a free movement sufficient to throw the jaw G away from the jaw B far enough for all practical purposes in releasing or picking up and gripping the cable.

5 The advantages of the counter-weight over the spring-power hitherto employed to open the jaw consist in its readiness to act at all times without any diminution in force, and 10 without occasion for renewal, while its weight is of small consideration, as it is applied at quite a distance above the bottom of the grip.

The wearing plates or blocks which are attached to the jaws admit of renewal at a slight 15 expense, and form a very efficient and economical grip-surface.

As the cable is grasped between the jaws the upright rollers first come in contact with it and form a partial hold, perhaps giving the 20 ear its first impulse, and in any event preventing the cable from chafing against the soft-metal plates as it approaches their surfaces, and yet when the jaws are firmly brought together the said rollers readily yield and allow 25 the metal plates to grasp the cable firmly.

It is evident that slight changes might be resorted to in the form and arrangement of the several parts described without departing from the spirit and scope of my invention; 30 hence I do not wish to limit myself strictly to the construction herein set forth; but,

Having fully described my invention, what I claim as new, and desire to secure by Letters Patent, is—

35 1. In a grip for cable railways, the combination, with a stationary jaw, of a movable jaw adapted to be swung away from the stationary jaw by a counter-weight, substantially as set forth.

40 2. In a grip for cable railways, the combination, with the hanger or grip-support and a stationary jaw secured to one side of the hanger or support, of a movable jaw hinged to the opposite side of the hanger or support, and

45 a counter-weight attached to the upper part of the hinged jaw, substantially as set forth.

3. In a grip for cable railways, the combination, with a stationary jaw provided with upright rollers secured yieldingly thereto, of a swinging jaw provided with upright rollers 50 secured yieldingly thereto, and with a pair of horizontal rollers secured to its lower edge, substantially as set forth.

4. In a grip for cable railways, the combination, with a gripping-jaw having upright 55 rollers journalled in bearings secured thereto, of a removable wearing-plate secured to the face of said jaw between the upright rollers, substantially as set forth.

5. In a grip for cable railways, the combination, with the gripping-jaws having upright rollers journalled in yielding bearings, 60 of soft-metal wearing plates or blocks removably secured to the jaws between the rollers, substantially as set forth.

6. The grip consisting, essentially, of the stationary jaw, with the upright rollers, and removable wearing-plate, the swinging jaw, with the upright rollers, removable wearing-plate, horizontal supporting - rollers, and counter-weight, and the cam or eccentric for closing the jaws, constructed and arranged substantially as set forth.

7. In a grip for cable railways, the combination, with a stationary jaw provided with 75 the removable metallic wearing plate or block between two or more yielding rollers, of a movable jaw provided with the removable metallic wearing plate or block between two or more yielding-rollers, said plates or blocks 80 forming a gripping-surface for the cable when they are pressed against the same after the rollers recede, substantially as set forth.

In testimony whereof I have signed this specification in the presence of two subscribing witnesses.

EDWARD D. DOUGHERTY.
